HARMONIC GENERATOR

Norman B. Blake, Beaumont, Tex., assignor to
Sun Oil Company, Philadelphia, Pa., a corpora-
tion of New Jersey

Application September 12, 1946, Serial No. 696,587

7 Claims. (Cl. 250—27)

1

This invention relates to a harmonic generator designed to secure a maximum output of upper harmonics of a fundamental frequency.

It sometimes happens that it is desired to secure a series of harmonics of some fundamental frequency for the purpose, for example, of establishing harmonic bands for simultaneous or inter-related uses. As an example, there may be cited multiple recording of signals on a single magnetic tape or wire. As an example illustrative of this, reference may be made to the application of Alfred C. Winterhalter, Serial Number 656,803, filed March 25, 1946, in which the harmonic generator of the present invention is employed for the purpose of securing a series of harmonically related bands modulated by separate signals and adapted to be simultaneously recorded. In general, the requirements of such a harmonic generator involve the transformation of a sinusoidal fundamental frequency wave into a wave having a rectangular or similar shape with sharp breaks in its outline of such nature that a Fourier analysis will show a high content of harmonics. In accordance with the present invention substantial outputs of harmonics ranging up to the fifteenth or higher may be secured.

The object of the present invention is the provision of means for securing harmonic outputs of the type just indicated. This object, together with other objects relating to details will become apparent from the following description read in conjunction with the accompanying drawing in which:

Figure 1 illustrates in diagram a preferred circuit embodying the invention; and

Figure 2 shows wave forms of the voltages at various points in the circuit.

Essentially, the circuit involves an oscillator delivering a sinusoidal output to a circuit giving rise to the harmonics of the oscillator frequency.

The oscillator 2 may comprise a tuning fork 40 having a frequency, for example, of 500 cycles, together with its driving system. The driving coil indicated at 42 is energized by the driving system which includes the pick-up 44, the amplifier tube 46 and its connections and the amplifier tube or tubes 48 illustrated as a twin triode, one section of which through the line 50 energizes the driving coil 42 and the other section of which through the line 52 feeds the output transformer 54, the output being delivered through the lines 56 and 57. The system here involved is essentially conventional for the driving of a tuning fork and need not be described in further detail,

2

the functions of the circuit being well understood by those skilled in the art.

The lines 56 and 57 feed the harmonic generator which is of novel construction, the induced voltage in the secondary of the transformer 54 being a substantially pure sine wave. The line 56 is connected to the anode 60 of a gas-filled rectifier tube 58, such as an 0Z4 (with its anodes connected together), the cathode 62 of which is connected through a battery 64 to the line 57. Beyond the connection to the anode 60, the line 56 includes a resistor 66 and is beyond this resistor connected to the cathode 70 of a diode 68, the anode 72 of which is connected through a battery 74 to the line 57. A twin diode, such as indicated, for example a 7A6, may be used with its cathodes and anodes connected together, as illustrated, to form, in effect, a single diode. The output is fed through a condenser 76, across a resistor 78 so that the harmonics which are generated are delivered through lines connected to the ends of the resistor. The battery 64 may have a voltage of 90 volts, and battery 74 a voltage of 22 volts for the particular tubes indicated.

The operation of the harmonic generator may be described as follows. As the input wave rises positively from a zero value in the line 56, no current will flow through the tube 58 until the anode-cathode voltage in that tube rises to the firing value which in the instance indicated may be about 300 volts. Prior to firing, therefore, the line 56 will rise to a voltage of, say, 210 volts with reference to line 57. Since the cathode 70 of the tube 58 is then positive, it cannot conduct. After firing, the anode-cathode drop in tube 58 becomes approximately 24 volts, and a heavy surge of current occurs through the tube.

The line 56 will accordingly become negative with respect to the line 57 by an amount equal to the difference between the voltage of the battery 64 and the voltage drop through the tube 58, i. e., in the example given, by 66 volts. Tube 58 will then remain conductive through the remainder of the positive half cycle and during the beginning of the negative half cycle until the applied voltage reached a negative value of 66 volts whereupon the tube 58 will be extinguished and the line 56 will thereafter have, relative to the line 57, a negative potential corresponding to the remaining half cycle of the voltage induced in the secondary of the transformer 54.

If the output were taken directly from the lines 56 and 57, the negative swing thus involved would introduce a considerable fundamental component into the output adding to the problem of

filtering. Furthermore, this negative swing would reduce the amplitude of some of the higher harmonics. The function of the combination of the diode 68 and resistor 66 is to remove by limiting action the negative voltage swings. This action may be explained as follows:

When the anode 60 becomes negative by the amount of 66 volts with respect to line 57, the battery 74 would, if the diode were non-conducting, cause the anode 72 of the diode to become positive with respect to its cathode by 66 volts plus the potential of battery 74, i. e., 88 volts in the example given. Actually the diode is conductive, and the voltage drops through the resistance 66 and the diode will cause the potential at the right of resistance 66 to become slightly positive with respect to the line 57. This condition continues until the tube 58 is extinguished. Thereupon the line 56 becomes more negative as the negative half cycle approaches its peak and cathode 70 may become slightly negative with respect to line 57. Following the peak of the negative half cycle, the potential of the cathode rises until early in the next positive half cycle when cut off occurs and the diode becomes non-conducting. Both tubes will then be non-conducting and consequently the potential at the right of resistance 66 with respect to line 57 follows the positive half cycle of voltage induced in the transformer secondary until the voltage is sufficiently high for the tube 58 to fire.

The foregoing will become apparent from an examination of Figure 2 in which wave form A is the substantially pure sine wave induced in transformer 54. Oscillogram B shows the voltage wave form across lines 56 and 57 wherein b_1 is the sine wave voltage curve existing up to a value of 210 volts. At this value, tube 58 becomes conductive and the voltage across conductors 56 and 57 drops to a negative 66 volts as shown in b_2 . This voltage continues until the impressed sine wave becomes more negative than 66 volts whereupon tube 58 is extinguished and the voltage wave proceeds through the remainder of the normal negative half cycle as shown in b_3 . Oscillogram C shows the output voltage of the harmonic generator wherein the voltage rise c_1 reaches a peak somewhat lower than 210 volts due to the voltage drop across resistor 66. The voltage drop is arrested at a low positive value c_2 when the diode 68 becomes conductive. This condition continues until tube 58 is extinguished and thereupon the voltage becomes more negative at c_3 until slightly before the end of the negative half cycle.

As a result of the foregoing, the output voltage consists of sharp peaks of substantially sinusoidal rises followed by steep drops with low and negligible values between these peaks. The wave thus produced has a high harmonic content containing large amplitudes of even such high harmonics as the fifteenth.

It will be evident that various changes may be made in details without departing from the scope of the invention as defined in the following claims.

What I claim and desire to protect by Letters Patent is:

1. A harmonic generator comprising a pair of input lines, a gas-filled tube having its anode connected to one of said lines and its cathode connected to the other of said lines through a source of direct potential having its negative terminal connected to said cathode, a thermionic rectifier with its cathode connected to the first line and its anode connected to the second line through

a source of direct potential having its positive terminal connected to the last mentioned anode, and means for supplying alternating current to said lines.

5. A harmonic generator comprising a pair of input lines, a gas-filled tube having its anode connected to one of said lines and its cathode connected to the other of said lines through a source of direct potential having its negative terminal connected to said cathode, a rectifier connected to the first line and through a source of direct potential to the second line, the rectifier being conductive when its terminal connected to the first line is negative, and the last mentioned source of direct potential having its negative terminal connected to said second line, and means for supplying alternating current to said lines.

3. A harmonic generator comprising a pair of input lines, a gas-filled tube having its anode connected to one of said lines and its cathode connected to the other of said lines through a source of direct potential having its negative terminal connected to said cathode, a rectifier connected to the first line and through a source of direct potential to the second line, the rectifier being conductive when its terminal connected to the first line is negative, and the last mentioned source of direct potential having its negative terminal connected to said second line, there being a resistance in the first line between the connections of the tubes thereto, and means for supplying alternating current to said lines.

4. A harmonic generator comprising a pair of input lines, a gas-filled tube having its anode connected to one of said lines and its cathode connected to the other of said lines through a source of direct potential having its negative terminal connected to said cathode, a thermionic rectifier with its cathode connected to the first line and its anode connected to the second line through a source of direct potential having its positive terminal connected to the last mentioned anode, there being a resistance in the first line between the connections of the tubes thereto, and means for supplying alternating current to said lines.

5. A harmonic generator comprising a pair of input lines, a gas-filled rectifier tube having its anode connected to one of said lines and its cathode connected to the other of said lines through a source of direct potential having its negative terminal connected to said cathode, a rectifier tube with its cathode connected to the first line and its anode connected to the second line through a source of direct potential having its positive terminal connected to the last mentioned anode and means for supplying alternating current to said lines.

6. A harmonic generator comprising a pair of input lines, a series arrangement of a gas filled tube and a source of direct potential connected across said lines with said source connected to oppose the flow of current through the tube, a series arrangement of a rectifier and a source of direct potential connected across said lines with the last mentioned source connected to oppose the flow of current through the rectifier, said tube and said rectifier being conductive in opposite directions between said lines, there being a resistance in one of said lines between its junctions to the two series arrangements, and means for supplying alternating current to said lines.

7. A harmonic generator comprising a pair of input lines, a series arrangement of a gas filled tube and a source of direct potential connected across said lines with said source connected to

oppose the flow of current through the tube, a series arrangement of a rectifier and a source of direct potential connected across said lines with the last mentioned source connected to oppose the flow of current through the rectifier, said tube and said rectifier being conductive in opposite directions between said lines, there being a resistance between the junctions of the two series arrangements to the input line which is of positive polarity when current flows through the gas filled tube, and means for supplying alternating current to said lines. 10
